UNITED STATES PATENT OFFICE.

FRANCIS A. WAGNER, OF DAYTON, OHIO.

STRUCTURAL TOY.

1,171,816.

Specification of Letters Patent. Patented Feb. 15, 1916.

Application filed April 30, 1915. Serial No. 24,863.

To all whom it may concern:

Be it known that I, FRANCIS A. WAGNER, a citizen of the United States, residing at Dayton, in the county of Montgomery and State of Ohio, have invented certain new and useful Improvements in Structural Toys, of which the following is a specification, reference being had therein to the accompanying drawing.

19 This invention relates to structural toys and more particularly to that type of structural toy comprising a plurality of parts, such as strips, plates and the like, each having a series of openings to receive fastening devices whereby the several parts may be connected together in different arrangements and combinations to produce structures of different kinds.

The object of the invention is to produce 20 an element for use in structures of this kind of such a construction that it can be used in a large number of different arrangements and combinations to produce a correspondingly large number of different structures; 25 and to so form this structural element that it may be held in rigid engagement with the parts to which it is connected by a minimum number of fastening devices.

It is also an object of the invention to provide 30 other parts or elements coöperating with said structural element to produce different structures.

It is a further object of the invention to produce a truck which can be adjusted to 35 different widths to accommodate it to different tracks and of such a character that it may embody a single pair of wheels or may be extended to embody a plurality of pairs of wheels.

40 In the accompanying drawings, Figure 1 is a perspective view of a truck embodying my invention; Fig. 2 is a perspective view of a portion of a truck showing a fifth wheel construction; Fig. 3 is a perspective view of 45 one of the structural elements; and Fig. 4 is a perspective view of a portion of a frame construction forming part of a building or shed.

In these drawings I have shown two different structures embodying my invention 50 and it will be understood that these particular structures are chosen for the purpose of illustrating the invention and the manner of its use.

55 In Fig. 3 of the drawings I have shown in detail the structural element forming the

basis both of the construction shown in Fig. 1 and of that shown in Fig. 4. This element comprises a plate 1 having its lateral edges converging toward one end and provided at 60 its opposite or wider end with a flange 2 extending at substantially a right angle to the plane of the body of the plate and, in the present instance, of a length slightly greater than the width of the widest portion of the plate, although this is not essential. The flange 2 and the adjacent portion of the body of the plate are respectively provided with a series of holes 3 and 4 extending longitudinally of the flange and adapted 70 to receive fastening devices, such as bolts. The body of the plate is also provided with a series of openings 5 arranged centrally thereof on a line extending transversely to the length of the flange 3. Preferably, the 75 plate is embossed to form channels 6 and 7 extending parallel with the series of openings 4 and 5, respectively, and having these series of openings arranged substantially centrally thereof. These channels are of a 80 depth and width to adapt them for the reception of a standard structural element or strip and when such a strip is placed in the channel, as will be hereafter explained, it may be rigidly connected thereto and the 85 parts held against relative displacement by the use of a single fastening device. The plate may be formed of any suitable material but I preferably employ a thin sheet steel which can be readily worked with dies. 90

In Fig. 1 of the drawings I have illustrated a truck, the frame of which consists of a plurality of the structural elements 1 connected together and provided with wheels. In constructing this truck I have 95 employed four plates or elements 1 and have connected these plates together in pairs, the flanges of each plate extending inwardly. Mounted in the lowermost hole 5 of opposed plates 1 are axles 8, to the outer 100 ends of which are secured wheels 9, the wheels being preferably adjustably secured to the axles, by means of set screws, for a purpose which will hereinafter appear. The plates may be connected together in any 105 suitable manner. In the present instance I have provided a structural element especially adapted for this purpose. This element comprises a plate having an elongated body portion 10 provided on its opposite sides with depending flanges or projections 11. The space between these flanges being 110

substantially equal to the width of the flanges 2 so that the flanges 2 will fit snugly between the flanges or projections on the elongated plate 10 when the latter is placed upon the flanged end of the plate 1. This elongated plate is provided with a longitudinal series of holes 12, to receive fastening devices. As shown in Fig. 1 the elongated plates 10 overlap the adjacent ends of the plates 1 of the respective pairs of plates and are secured thereto by suitable fastening devices, such as bolts 13. The plates 1 are shown with their flanges abutting one against the other and the fastening devices are inserted in the second hole from the end of each flange. It will be obvious that by altering the point of connection between the plates the length of the truck can be varied. Further, it will be apparent that because of the channel or flange construction of the elongated plates a single fastening device at each end of the elongated plate is sufficient to rigidly connect it to the two plates. When this elongated plate has been secured to two of the plates 1 the three plates constitute a complete side frame member for the truck. The two side frame members may be connected one to the other in any suitable manner and I preferably provide the structural element 10 with a laterally extending portion 14 having projections or flanges 15 near the outer ends thereof to form channels. Extending between the two plates 10, and having its end portions lying within the channels formed by the projections 15 is a structural element 16 constituting a connecting device for the side frame members. This connecting device is preferably adjustable with relation to the side members to vary the width of the truck and to this end the openings for the fastening devices are in the form of elongated slots 17. By adjusting the fastening devices along these slots any desired width of truck, within two extreme limits, may be secured and by shifting the wheels 9 on their axles, by loosening the set screws, they may be adjusted to correspond to the width of the truck frame, and may be placed either inside or outside of the side frame members. The connecting device 16 is shown as provided centrally with an offset or elevated portion 18 to receive a bolster or other car supporting structure.

By securing a second connecting device in inverted position upon the first connecting device and securing the two devices together by means of a single bolt 19, as shown in Fig. 2, a fifth wheel or steering construction may be produced, it being noted that the offset portions 18 of the connecting devices space the upper and lower structures apart in such a manner as to allow a free turning movement. As shown in Fig. 2 I have provided the upper connecting device

16 of the fifth wheel, at each end, with a structural element 10, these elements being arranged with their flanges turned upward and being adapted to receive a frame member of a car or other structure. It will be apparent that the length of the truck may be varied to adapt the same for use with one pair of wheels or a plurality of pairs of wheels. By the use of additional structural elements the length of the truck can be extended indefinitely. If it is desired to use a single pair of wheels the structural elements 10 are placed directly above the structural elements 1 so that the connecting device 16 will be placed directly above the axle. 70 75 80

In Fig. 4 of the drawings I have illustrated the structural element or plate 1 as forming a connecting device, by means of which the foot of a column or upright member 20 is secured to a base plate 21. It will be noted that the column comprises a strip 20 of standard construction which is placed within the channel 7 and secured thereto by a fastening device. The flange 2 rests upon and is secured to the apertured base plate 21 so that the frame member 20 is held in a rigid vertical position relatively thereto. Secured to the upper end of the frame member 20 are two other structural elements 22 of similar construction and especially adapted for forming corner braces, or for forming supporting brackets for overhanging structures, such for example as a train shed where the roof projects on opposite sides of a row of central supports, such as the column or frame member 20. The structural elements 22 each comprises a plate approximately triangular in form and having two of its edges arranged at a right angle one to the other and provided along these edges with two series of openings 23 and 24. The portions of the plate containing these openings are flat and are adapted to rest upon and to be secured to other structural elements, such as the angle bar shown at 25. With a sufficient number of the structural elements shown in Fig. 4 a great variety of building constructions may be made, it being apparent that the parts may be arranged in various positions and may be connected in various combinations. 90 95 100 105 110 115

The construction and manner of use of the several parts of the invention will be readily understood from the foregoing description and it will be apparent that these parts are of a very wide utility, can be used in many different constructions and when so used produce a very rigid structure; and further, can be assembled, and such rigid structure produced, by the use of a minimum number of fastening devices. Further, the shapes of the parts are such that the finished structure bears a marked resemblance to actual steel structures. 120 125 130

While I have shown and described the

parts of particular shapes and have shown these parts in various combinations I wish it to be understood that I do not desire to be limited to the details of construction shown and described, for various modifications will occur to one skilled in the art.

Having thus fully described my invention, what I claim as new and desire to secure by Letters Patent, is:—

- 10 1. A structural element for a toy comprising a plate having its lateral edges converging toward one end thereof and having at its wider end a flange extending at an angle to the plane of said plate, said flange having a series of openings arranged parallel with the plane of said plate to receive fastening devices to connect said plate with other parts of the toy structure, and said plate having a series of similar openings in the body portion thereof adjacent to and parallel with said flange and also having a series of similar openings arranged medially thereof in a line extending at substantially right angles to said flange.
- 15 2. A structural element for a toy comprising a plate having its lateral edges converging toward one end thereof and having at its wider end a flange extending at an angle to the plane of said plate, said flange having a series of openings arranged parallel with the plane of said plate to receive fastening devices to connect said plate with other parts of the toy structure, and said plate having a depressed portion arranged near and parallel with said flange and forming a channel to receive another element of the toy structure, said plate also having a similar depressed portion arranged centrally thereof and at right angles to the first-mentioned depressed portion and each of said depressed portions having openings to receive fastening devices.
- 20 3. A structural element for a toy comprising a plate having at one end a flange extending at an angle to the plane of said plate, said flange having a series of openings arranged parallel with the plane of said plate to receive fastening devices to connect said plate with other parts of the toy structure and said plate having a depressed portion arranged adjacent to and parallel with said flange to form a channel to receive another element of the toy structure, said plate also having a similar depressed portion arranged substantially centrally thereof and at right angles to the first-mentioned depressed portion, and each of said depressed portions having openings to receive fastening devices.
- 25 4. A structural element for a toy comprising a plate having at one end a flange extending at an angle thereto and having its other end of a width less than the width of the flanged end, said flange and the narrow end of said plate having openings, a second plate having an elongated portion provided with projections arranged to engage the opposite edges of said flange when said second plate is placed in engagement with said flange, said elongated portion of said second plate having openings and said second plate also having a laterally extending portion to connect the same to another part of said toy structure, said laterally extending part having an opening to receive a fastening device.
- 30 5. A structural element for a toy comprising a plate having at one end a flange extending at an angle thereto and having its other end of a width less than the width of the flanged end, said flange and the narrow end of said plate having openings, a second plate having an elongated portion provided with projections arranged to engage the opposite edges of said flange when said second plate is placed in engagement with said flange, said elongated portion of said second plate having openings and said second plate also having a laterally extending portion to connect the same to another part of said toy structure, said laterally extending part having an opening to receive a fastening device, and a connecting device adjustably secured to the laterally extending portion of said second plate.
- 35 6. A structural element for a toy comprising a plate having at one end a flange extending at an angle thereto and having its other end of a width less than the width of the flanged end, said flange and the narrow end of said plate having openings, a second plate having an elongated portion adapted to engage said flange, said elongated portion of said second plate having openings and said second plate also having a laterally extending portion to connect the same to another part of said toy structure, said laterally extending part having an opening to receive a fastening device.
- 40 7. A structural element for a toy comprising a part having a portion provided with openings to receive fastening devices, a plate having an elongated portion to engage said part and having a laterally extending portion, said elongated portion of said plate having projections to engage the edges of said part and said elongated portion and said laterally extending portion having openings to receive fastening devices.
- 45 8. In a toy structure, a truck comprising side members each consisting of a plate having a reduced lower portion provided with an opening and having at its upper end a flange extending at an angle to the body of the plate and provided with a series of openings, other plates resting upon and secured to the flange of the respective side plates, and a connecting device extending between and secured to said other plates, an

second plate having an elongated portion provided with projections arranged to engage the opposite edges of said flange when said second plate is placed in engagement with said flange, said elongated portion of said second plate having openings and said second plate also having a laterally extending portion to connect the same to another part of said toy structure, said laterally extending part having an opening to receive a fastening device.

50 9. A structural element for a toy comprising a plate having at one end a flange extending at an angle thereto and having its other end of a width less than the width of the flanged end, said flange and the narrow end of said plate having openings, a second plate having an elongated portion provided with projections arranged to engage the opposite edges of said flange when said second plate is placed in engagement with said flange, said elongated portion of said second plate having openings and said second plate also having a laterally extending portion to connect the same to another part of said toy structure, said laterally extending part having an opening to receive a fastening device, and a connecting device adjustably secured to the laterally extending portion of said second plate.

55 10. A structural element for a toy comprising a plate having at one end a flange extending at an angle thereto and having its other end of a width less than the width of the flanged end, said flange and the narrow end of said plate having openings, a second plate having an elongated portion provided with projections arranged to engage the opposite edges of said flange when said second plate is placed in engagement with said flange, said elongated portion of said second plate having openings and said second plate also having a laterally extending portion to connect the same to another part of said toy structure, said laterally extending part having an opening to receive a fastening device.

60 11. A structural element for a toy comprising a part having a portion provided with openings to receive fastening devices, a plate having an elongated portion to engage said part and having a laterally extending portion, said elongated portion of said plate having projections to engage the edges of said part and said elongated portion and said laterally extending portion having openings to receive fastening devices.

65 12. In a toy structure, a truck comprising side members each consisting of a plate having a reduced lower portion provided with an opening and having at its upper end a flange extending at an angle to the body of the plate and provided with a series of openings, other plates resting upon and secured to the flange of the respective side plates, and a connecting device extending between and secured to said other plates, an

70 13. A structural element for a toy comprising a plate having at one end a flange extending at an angle thereto and having its other end of a width less than the width of the flanged end, said flange and the narrow end of said plate having openings, a second plate having an elongated portion provided with projections arranged to engage the opposite edges of said flange when said second plate is placed in engagement with said flange, said elongated portion of said second plate having openings and said second plate also having a laterally extending portion to connect the same to another part of said toy structure, said laterally extending part having an opening to receive a fastening device.

axle mounted in the openings in the reduced portions of said plates, and wheels mounted on said axle.

9. In a toy structure, a truck comprising side members each consisting of a plate having a reduced lower portion provided with an opening and having at its upper end a laterally extending flange and elongated plates resting upon and secured to the respective flanges and each having an inwardly extending portion, a connecting device extending transversely of said truck and adjustably secured at its ends to the inwardly extending portions of said elongated plates, axles mounted in openings in the reduced portions of said side plates, and wheels mounted on said axles.

10. In a toy structure, a truck comprising side members each consisting of a plate having a reduced lower portion provided with an opening and having a laterally extending flange at the upper end thereof, elongated plates adapted to rest upon the respective flanges and each having projections along its edges to engage the respective edges of said flanges, said flanges and said elongated plate having openings to receive fastening devices, each of said elongated plates having a laterally extending projection provided with an opening and having projections extending from one face thereof, a connecting device comprising a strip having its opposite ends slotted and adapted to rest upon the laterally extending portions of said elongated plates between the projections thereon.

11. In a toy structure, a truck comprising side members each consisting of a plate having a reduced lower portion provided with an opening and having a laterally extending flange at the upper end thereof, elongated plates adapted to rest upon the respective flanges and each having projections along its edges to engage the respective edges of said flanges, said flanges and said elongated plate having openings to receive fastening devices, each of said elongated plates having a laterally extending projection provided with an opening and having projections extending from one face thereof, a connecting device comprising a strip having its opposite end slotted and adapted to rest upon the laterally extending portions of said elongated plates between the projections thereon, said connecting device having an elevated portion intermediate its ends to form a support for a superstructure.

12. In a toy structure, a truck comprising side members each consisting of a plate having a reduced lower portion provided with an opening and having a laterally extending flange at the upper end thereof, elongated plates adapted to rest upon the respective flanges and each having projections along its edges to engage the respective edges of

said flanges, said flanges and said elongated plate having openings to receive fastening devices, each of said elongated plates having a laterally extending projection provided with an opening and having projections extending from one face thereof, a connecting device comprising a strip having its opposite ends slotted and adapted to rest upon the laterally extending portions of said elongated plates between the projections thereon, said connecting device having an elevated portion intermediate its ends to form a support for a superstructure, a second connecting member arranged above the first connecting member in an inverted position and pivotally connected to the elevated portion of said first connecting member, said second connecting member having secured to its opposite ends devices for supporting a superstructure.

13. In a toy structure, a truck comprising side members, each of said side members consisting of a plurality of plates, each of said plates having a reduced lower portion provided with an opening and also having a laterally extending flange at its upper end, the plates of each side member being arranged with their flanges in alinement, each side member further comprising an elongated plate having its ends overlapping and secured to the adjacent ends of said flanges, each of said elongated plates having a laterally extending portion, and a connecting member interposed between said side frame members and having its ends adjustably connected with the lateral portions of said elongated plate, axles mounted in the lower portions of opposed side plates, and wheels mounted on said axles.

14. In a toy structure, a truck comprising side members, a connecting member extending between said side members and having an intermediate portion offset and arranged in a plane substantially parallel with, and above, the end portions thereof, a second member arranged above said connecting member and having an intermediate portion offset and arranged in a plane below and substantially parallel with the end portions thereof, the offset portions of said members being pivotally connected one to the other and said last-mentioned member having means for connecting a superstructure thereto.

15. In a toy structure, a truck comprising a set of side members at each side of the truck, axles carrying wheels and mounted in said members, an elongated plate connecting together the side members of each set, and a transverse member overlapping said plates, one of the overlapping parts being slotted to permit the width of the truck to be minutely varied.

16. In a toy structure, a truck comprising a set of side members at each side of the

truck, each of these members having a series of perforations, axles carrying wheels and mounted in said side members, an elongated plate connecting together the side members of each set, and having perforations to operate with the perforations in the side members, so that the length of the truck can be varied, and a transverse member overlapping said plates, one of the overlapping

parts being slotted to permit the width of the truck to be minutely varied, whereby a truck of variable lengths and widths may be made of the same elements, and suitable fastening devices for securing the parts together.

In testimony whereof, I affix my signature.

FRANCIS A. WAGNER.
